To all whom it may concern:

Be it known that I, PEARL N. Figure 1 is a front view of a fare token embodying my new design; and Figure 2 is a back view of the same.

I claim:

The ornamental design for a fare token, as shown.

In witness whereof, I have hereunto set my hand.

PEARL N. JONES.

Certificate of Correction.

It is hereby certified that the assignment in Design Letters Patent No. 62,820, granted August 7, 1923, upon the application of Pearl N. Jones, of Pittsburgh, Pennsylvania, for a "Design for a Fare Token," was erroneously described and specified as "C. A. Fagan, W. D. George, and S. L. Tone, receivers, of Pittsburgh, Pennsylvania," whereas said assignment should have been described and specified as *C. A. Fagan, W. D. George, and S. L. Tone, receivers of Pittsburgh Railways Company, of Pittsburgh, Pennsylvania, a Corporation of Pennsylvania*, as shown by the records of assignments in this office; and that the said Letters Patent should be read with this correction therein that the same may conform to the record of the case in the Patent Office.
